UNITED STATES PATENT OFFICE.

SIDNEY A. KELLER, OF NEW YORK, N. Y.

DESIGN FOR A HANDLE FOR BUTTON-HOOKS, &c.

SPECIFICATION forming part of Design No. 31,547, dated September 26, 1899.

Application filed July 27, 1899. Serial No. 725,324. Term of patent 3 $\frac{1}{2}$ years.

To all whom it may concern:

Be it known that I, SIDNEY A. KELLER, a citizen of the United States, and a resident of New York, in the county of New York and State of New York, have invented a certain new and useful Design for Handles for Button-Hooks and Similar Articles, of which the following is a specification, wherein reference is made to the accompanying drawing and the

letters thereon, which form a part of this application and which show the article in elevation and together furnish a clear and exact description of my design, which is essentially as follows:

The leading feature of my design is a handle for button-hooks and similar articles ornamented by a panel inclosed by conventional roses and leaves, which in turn are surrounded by a succession of bulb-shaped lobes, (or stems.)

More particularly described, it consists of a succession of conventional rose garlands, (marked K G M,) separated from one another by the conventional fleur-de-lis I J and the 5 trilobes, (marked O.)

The bulb-shaped lobes (or stems) D E F form the contour of the upper part of the design and are in high relief to the roses and leaves which form the outline of the panel C, giving the whole upper design a lens-shaped 30 appearance.

The base of the design rests upon two sections of a sphere and consists of a number of buds L.

The panel C is ornamented to the left as 35 described to the right.

Having thus described my invention, what I claim as new, and desire to secure by Letters Patent, is—

The design for a handle for button-hooks 40 and similar articles substantially as herein shown and described.

Signed at New York, in the county of New York and State of New York, this 21st day of July, A. D. 1899.

SIDNEY A. KELLER.
